UNITED STATES PATENT OFFICE.

JOHN HAMPSON, OF LONDON, ENGLAND.

GAME APPARATUS.

Application filed July 7, 1921. Serial No. 483,043.

(GRANTED UNDER THE PROVISIONS OF THE ACT OF MARCH 3, 1921, 41 STAT. L., 1313.)

To all whom it may concern:

Be it known that I, JOHN HAMPSON, a subject of the King of Great Britain and Ireland, residing at 9 Campden Hill Gardens, 5 London, W. S., England, have invented certain new and useful Improvements in Game Apparatus (for which I have filed application for patent in England, No. 161,757, 5 February, 1920), of which the following is 10 a specification.

This invention refers to game apparatus and relates more particularly to apparatus of the class in question for playing a "race game" in which the horses or other moving 15 figures are drawn along by means of cords wound upon suitable devices adapted to be operated by the players. The playing surface may comprise a table or the like, a lawn or the deck of a ship, or any other 20 suitable surface.

In games of this type it has been proposed to provide the winding spindle with a skeleton drum having a number of removable bars formed with an undulating edge, the 25 bars being arranged to produce a certain amount of lateral slip, which provides for the uncertainty of the speed of travel of the models.

In some cases the spindle on which the 30 cord is wound is rotated in a chamber into which foreign bodies are introduced which are caught up in the coils of the winds to cause the model to be drawn in more rapidly.

35 In these constructions, however, there is no movement or manipulation of the fitting or the like supporting the winding spindle or drum.

According to my present invention, I provide for each of the players, a device or 40 fitting adapted to be rocked or manipulated, said fitting having a spindle operated by a handle and carrying a drum or the like having an irregular surface, so that considerable 45 skill is necessitated on the part of the player in manipulating his device in order to cause the horse or other model to be moved with the maximum velocity.

In one particular construction according 50 to my invention, I provide a stirrup shaped fitting, which is held in an inverted position upon a holder and this holder preferably comprises a bracket or base plate bent at right angles and fitted with a suitable handle

and a leg or the like, so that it can be rested 55 over and against the edge of the table upon which the game is being played, or the bracket may be supported on a suitable pedestal, on a lawn or other surfaces on which the models are caused to travel. 60

Rotatably mounted in bearings in the said stirrup shaped fitting is a spindle, furnished with an operating handle beyond one of the bearings.

Suitably formed or mounted on the said 65 spindle is the device upon which the cord is to be wound, and in the preferred construction, this is of double conical form, with the bases of the cones, adjacent one another.

Disks or flanges may be provided between 70 the conical surfaces and the bearings to prevent the cord being drawn into the bearings.

With this construction, the end of the cord is attached to the winding device, for instance, at the point between the two conical surfaces, and the cord is wound up drawing the figure in with it by turning the handle. It will be obvious that there is a tendency for the cord to roll down the conical surface on one side or the other of the 80 maximum diameter and consequently to decrease the speed with which the figure is moved and the skill of the player is brought into play by so manipulating the device carrying the winding mechanism that the cord 85 is always kept over the conical surface of the largest diameter.

In order that the invention may be readily understood reference is made to the accompanying drawing in which:— 90

Fig. 1 is a side view and Fig. 2 a plan of one form of the apparatus for playing a game, according to the invention.

Fig. 3 is an end view of Fig. 1, seen from the right. 95

Fig. 4 and Fig. 5 are perspective views of two modified constructions of the apparatus.

According to the invention, each of the players is provided with a device shown in the drawings, which comprises a stirrup shaped fitting or frame having a handle portion and supports carrying a drum, roller or its equivalent operated by a suitable handle. 100

In the construction shown in Fig. 1, the frame is bent to the required shape from a single strip of metal of suitable construction, the ends *a* of the strip extending upwardly

at a suitable distance apart to form bearings for a spindle *b*. The spindle *b* is provided at one end with a cranked handle *c* and with a drum like portion *d* located centrally between the members *a*. This drum like portion *b* may be of any desired irregular shape, but is preferably formed cylindrical at the centre and conical at the ends as shown in the drawings. The spindle *b* 5 also has fixed thereto, just on the inner side of the bearings, a disc or plate *f*, serving to retain the cord *g* on the winding portion of the spindle. The ends *a* of the frame are bent inwardly towards one another at *h* 10 and then rearwardly at *i* to form a handle *k*, a binding clip or ring *h* being preferably employed to secure the two parts together at the handle as shown. The portion *i* immediately behind the stirrup shaped frame 15 *a*, *b* is also provided with a depending leg rod or strip *m*, for a purpose hereinafter more fully described.

The apparatus is used in the following manner:—

25 The end of the cord is attached to the cylindrical portion of the winding device, as for instance by passing the same through a hole therein. The opposite end of the cord is passed through an eye or similar device 30 secured to a model which may have the form of a horse, vehicle or any other device to be drawn along a table or other surface. This end of the cord may be extended back to the fitting and tied or otherwise secured to 35 a stationary portion thereof. The stirrup shaped frame is now supported against the edge of the table *n* or the like, so that the leg or the like *m* forms a fulcrum about which the whole frame may be rocked in a 40 horizontal plane. The player now rotates the spindle by the handle *c* and in doing so uses his best endeavours to retain the windings or coils of the cord on the central portion of the winding spindle. The cord 45 will of course have a tendency to ride down the conical ends of the winding drum and the player has to manipulate the frame, so as to guide the cord onto the portion of the spindle of larger diameter, so that for each 50 rotation of the crank handle, *c*, the maximum length of cord will be wound up or drawn in, thus causing the model to approach the device at a greater speed.

In the construction shown in Fig. 4, the 55 frame is formed of sheet metal, the depending leg *m* being stamped out of the body of the handle whilst the ends *a* are bent at *a* to extend upwardly to support the winding device.

60 In the form illustrated at Fig. 5, the device is formed in two parts, the one part *k* constituting the handle being pivotally connected to a stirrup shaped member *m*, carrying the winding spindle. The member *n* carries at its upper end the spindle

b provided with the operating handle *c* whilst its lower end is pivoted to a rod *o* passing through lugs in the forked end of the portion *k* and is also provided with a centrally disposed projecting leg *m*. When 70 the apparatus is being used, the pressure of the leg *m* against the edge of the table or other surface maintains the winding spindle in the correct position, the portion *k*, *h* of the stirrup shaped frame abutting 75 against the under surface of the forked ends of the handle portion *k* whilst when the device is to be packed away, the pivotal connection between the two parts permits the device being folded substantially flat, as 80 shown in dotted lines.

In some cases a device may be formed in which a base plate is provided adapted to be clamped to the edge of a table or the like, and furnished with a standard, over which 85 fits a tubular socket or the like carrying the stirrup shaped fitting, which fitting is in that case provided with a separate handle or equivalent enabling it to be turned from side to side on the fixed standard, so as to enable the player to vary the angle at which the cord is drawn in.

It will be evident that in place of providing two adjacent conical surfaces, two flat wedge shaped surfaces may be provided or other irregular surfaces, requiring skill on the part of the player as well as quickness in winding in the cord. 90

In connection with the apparatus, for marking the starting and winning lines or 100 posts, I may provide weighted tapes or the like, which may be white or coloured, the weights being preferably adjustable, so that they can be adjusted over the edges of the table or the like as may be required.

105 It will be evident that the details of construction of the apparatus may be varied considerably without departing from the principle of the invention.

What I claim as my invention and desire 110 to secure by Letters Patent in America is:—

1. Apparatus for playing race games, comprising in combination a stirrup shaped fitting carrying a rotatable spindle provided 115 at one end with a handle and having a portion of its length formed as an irregular surface, a flexible member attached to a model and at one end to said spindle and supporting means for said fitting permitting the same to be manipulated in a horizontal plane during rotation of the spindle.

2. Apparatus for playing race games, comprising in combination, a fitting provided 120 with bearings, a spindle rotatable in said bearings, a handle at one end of said spindle, a drum having an irregular surface on said spindle, a flexible member connected at one end to said drum and operatively connected to a model, a supporting member on said fit- 125 130

ting, said member having a depending leg adapted to enable the device to be supported on and manipulated in a horizontal plane with respect to a surface over which said 5 model is to travel.

3. Apparatus for playing race games, comprising in combination, a fitting having a handle portion and a stirrup shaped fitting, a rotatable spindle supported in bearings, 10 in the sides of said fitting, a cylindrical surface on said spindle located between said bearings and having its ends reduced and tapered, a flexible cord attached at one end to said cylindrical surface and operatively 15 connected to a model, a handle at one end of said spindle, and supporting means for said fitting permitting the same to be rocked with respect to a playing surface over which the model is caused to travel.
- 20 4. Apparatus for playing race games, comprising in combination, a fitting having a handle portion and a stirrup shaped portion, bearings in said stirrup portion, a rotatable spindle in said bearings, an irregular 25 surface in said spindle formed by a cylindrical central portion and reduced and conical end portions, a flexible cord attached to said spindle and operatively connected to a model adapted to travel over a playing 30 surface, a handle on one end of said spindle and supporting means for said fitting per-

mitting the same to be rocked for the purposes set forth.

5. Apparatus for playing race games, comprising a fitting having a handle a stirrup 35 shaped member, pivotally connected to said fitting, a spindle rotatably supported in said member, a handle at one end of said spindle, an irregular surface on said spindle, supporting means for said fitting, permitting same 40 to be rocked with relation to a playing surface, and a flexible cord attached to said spindle, and to a model to be drawn over said playing surface.

6. Apparatus for playing race games, comprising a playing surface, a fitting having a handle, supporting means for said fitting, permitting the same to be rocked in a plane, substantially parallel with said playing surface, a spindle rotatably supported in said 50 fitting means for rotating said spindle, a drum having reduced conical ends on said spindle, disks on the spindle at the ends of the drum and a flexible cord attached at one end to said spindle and operatively connected to a model adapted to travel over said playing surface, when said spindle is rotated.

In testimony whereof, I have hereunto subscribed my name.

London 22 June 1921.

JOHN HAMPSON.
